(57) **CLAIM**

The ornamental design for an automobile, toy replica and/or other replica as shown and described.

DESCRIPTION

FIG. 1 is a left, front perspective view of an automobile, toy replica and/or other replica showing our new design;

FIG. 2 is a front elevation view thereof;

FIG. 3 is a top plan view thereof;

FIG. 4 is a left, rear perspective view thereof;

FIG. 5 is a rear elevation view thereof;

FIG. 6 is a left-side elevation view thereof; and,

FIG. 7 is a right-side elevation view thereof.

The broken lines shown throughout the drawing views are for environmental and illustrative purposes that form no part of the claimed design.

1 Claim, 7 Drawing Sheets
